CLAIM

The ornamental design for a cutting insert support/clamp, as shown and described.

DESCRIPTION

FIG. 1 is a perspective view of a cutting insert support/clamp showing my new design;

FIG. 2 is another perspective view of the cutting insert support/clamp showing my new design;

FIG. 3 is another perspective view of the cutting insert support/clamp showing the toolholder rotated 90 degrees from the position shown in FIG. 1;

FIG. 4 is a side elevational view of the cutting insert support/clamp;

FIG. 5 is another side elevational view of the cutting insert support/clamp;

FIG. 6 is a left end view (as viewed in FIG. 4) of the cutting insert support/clamp;

FIG. 7 is a right end view (as viewed in FIG. 4) of the cutting insert support/clamp;

FIG. 8 is a top plan view of the cutting insert support/clamp; and,

FIG. 9 is a bottom plan view of the cutting insert support/clamp.

The broken lines in FIGS. 1-5 and 7-9 are for illustrative purposes only and do not form part of the invention shown in FIGS. 1-9.
